UNITED STATES PATENT OFFICE.

GEORGE FULLARTON TAYLOR, OF LONDON, ENGLAND.

CONSTRUCTION OF MULTIPLE-ROLL CALENDER OR IRONING MACHINE.

1,323,121.

Specification of Letters Patent.

Patented Nov. 25, 1919.

Application filed April 11, 1919. Serial No. 289,319.

To all whom it may concern:

Be it known that I, GEORGE FULLARTON TAYLOR, a subject of the King of Great Britain, residing at London, England, have 5 invented certain new and useful Improvements in the Construction of Multiple-Roll Calender or Ironing Machines, of which the following is a specification.

The object of this invention is to construct a multiple roll calender or ironing machine in which the calendering or ironing is more efficiently performed, and the machine more convenient to work, the erection of same being also more easily accomplished.

15 For the purpose of this invention I position the rolls and concave beds in two inclined planes or curves the lower beds of which meet or have a separate bridge piece positioned between the two adjoining beds.

20 My invention will be clearly understood from the diagrams shown on the annexed drawings and in which Figure 1 is a section of eight rolls positioned in two planes and their beds, the beds having curved bottoms.

25 Fig. 2 is a section of eight rolls positioned in two planes and their beds the bottoms of the beds being so constructed that when joined form a smooth surface against which the articles being calendered can be passed by aprons in the well known manner.

In both figures the rolls A and beds B are positioned in two inclined planes with the lower beds meeting.

30 Steam is admitted to the two outside or upper beds B and travels through the beds toward the center or lower beds where it drains away.

35 The rolls A are capable of being raised *en masse* or singly, or in sections, as is well known, and all of the rolls are connected together by suitable gearing to revolve same at uniform speed and in the same direction and such driving may be through one pulley or a number of pulleys according to whether 40 all the rolls are in gear together or in sections.

45 By this invention the article to be cal-

endered is subjected to the greatest heat at its exit from the machine and in consequence is more perfectly acted upon and 50 more highly finished.

The frame carrying the rolls, beds, gear and other mechanism may be as a whole, or in sections bolted together.

In all multiple roll calenders or ironing 55 machines irrespective of the method of coupling up of the steam pipes, the tendency is for the whole of the condensation including that from main steam pipes leading to machine, to find its way to the last beds 60 over which the material is passed, the result being a lowering of the temperature, whereas, in those very beds, it is essential that the highest temperature be maintained. Now by this invention this feature of providing a high temperature at the last beds 65 is maintained, and with the preferred construction of machine, the wet, and therefore limp material by its passage over the first beds, which are arranged in a descending 70 plane or curve, has derived the rigidity necessary to pass up the other beds which are arranged on an ascending plane or curve.

By this invention the machine is kept at a more convenient height so that the trestles 75 on which the feeders stand may be dispensed with and the finished work is delivered at the proper height for easy handling by the folders.

What I do claim as my invention and desire to secure by Letters Patent, is:—

A multiple roll calender or ironing machine with the rolls and concave beds arranged in two inclined planes or curves with the lower beds adjacent to each other, 85 substantially as described and as shown on the annexed drawing.

In testimony whereof I have hereunto set my hand in presence of two subscribing witnesses.

GEORGE FULLARTON TAYLOR.
